Primary Examiner—Bernard Ansher*Assistant Examiner*—Philip Hyder*Attorney, Agent, or Firm*—Timmons & Kelly[57] **CLAIM**

The ornamental design for a tool for handling spring clips and paper clips, as shown and described.

DESCRIPTION

FIG. 1 is a front elevation of a tool for handling spring clips and paper clips showing my new design;

FIG. 2 is a left side elevation thereof;

FIG. 3 is a right side elevation thereof; and,

FIG. 4 is a top plan view thereof, the bottom plan view appearing identical thereto.
